United States Patent Office

Des. 220,690

Patented May 11, 1971

220,690

CHAIR

Arthur Charles Ferro, St. Louis, Mo., assignor to Contour Chair-Lounge Co., Inc., St. Louis, Mo.

Filed Mar. 16, 1970, Ser. No. 21,920

Term of patent 14 years

Int. Cl. D6—02

U.S. Cl. D15—11

FIG. 1 is a top plan view of a chair showing my new design;

FIG. 2 is a side elevational view thereof;

FIG. 3 is a rear elevational view thereof;

FIG. 4 is a front elevational view thereof; and

FIG. 5 is a side elevational view thereof, showing the side opposite to that of FIG. 2 and illustrating the pivotally mounted kneeling stool in use position.

I claim:

The ornamental design for a chair, as shown.
